UNITED STATES PATENT OFFICE.

PATRICK T. LARKIN, OF GREAT BARRINGTON, MASSACHUSETTS.

MUSIC-FILING CABINET.

1,259,419.

Specification of Letters Patent. Patented Mar. 12, 1918.

Application filed December 13, 1916. Serial No. 136,616.

To all whom it may concern:

Be it known that I, PATRICK T. LARKIN, a citizen of the United States, and a resident of Great Barrington, in the county of Berkshire and State of Massachusetts, have invented a new and Improved Music-Filing Cabinet, of which the following is a full, clear, and exact description.

The object of the invention is to provide 10 a new and improved music filing cabinet more especially designed for conveniently filing sheet and roll music and phonographic disk records and phonographic cylinder records and arranged to permit the user to 15 quickly locate and easily remove any one piece of music without disturbing any other piece.

In order to accomplish the desired result, 20 use is made of a cabinet provided with a number of sections each divided into compartments arranged one above the other, one of the compartments being for filing sheet music and phonographic disk records in upright position and this compartment being 25 provided with consecutively numbered and vertically disposed books each having its leaves numbered consecutively, another compartment being for filing roll music and having cells each adapted to receive a roll singly 30 and arranged in vertical and horizontal rows, the vertical rows being numbered consecutively, and a tray slidable transversely in the cabinet and provided with rows of 35 posts each adapted to receive a phonographic cylinder record singly, the posts in each row being numbered consecutively.

A practical embodiment of the invention is represented in the accompanying drawings forming a part of this specification, in 40 which similar characters of reference indicate corresponding parts in all the views.

Figure 1 is a front elevation of the music filing cabinet;

Fig. 2 is an enlarged transverse section 45 of the same on the line 2-2 of Fig. 1;

Fig. 3 is a perspective view of a portion of the index book in open position;

Fig. 4 is a perspective view of one end portion of a music roll and its identification 50 characters;

Fig. 5 is a perspective view of a portion of the cabinet showing the tray for holding the phonographic cylinder records in outward position;

55 Fig. 6 is a face view of a portion of a

piece of sheet music provided with identification characters; and

Fig. 7 is a face view of a phonographic disk record provided with identification characters.

The filing cabinet illustrated in Figs. 1, 2 and 5, consists preferably of two sections 10 and 11 arranged one alongside the other and separated by a vertical partition 12. The section 10 of the cabinet is divided by 65 a horizontal partition 13 into an upper compartment 14 and a lower compartment 15, and the section 11 is divided by a horizontal partition 16 into an upper compartment 17 and a lower compartment 18. The compartments 14, 17 and 18 are arranged for filing sheet music and phonographic disk records, and the compartment 15 is provided in its upper portion with a tray 20 for supporting phonographic cylinder records and the lower 75 portion of the compartment 15 is provided with cells or pigeon-holes 22 each adapted to receive a music roll 23 singly, as will be readily understood by reference to Fig. 1.

Each of the compartments 14, 17 and 18 is 80 provided with books 25 disposed vertically and arranged one alongside the other, the books in each compartment being identified by consecutive numerals 26 arranged on top of the books, as plainly indicated in Fig. 1. 85 Each of the books 25 has its leaves 27 hung on rods 28 fixed in the corresponding compartment 14, 17 or 18, and the leaves 27 in each book 25 are provided at their outer edges with index tabs 29 provided with 90 index numerals arranged consecutively, as will be readily understood by reference to Fig. 2.

The shelf 20 is provided with two rows of posts 30 and 31 each adapted to form a 95 support for a corresponding phonographic cylinder record 21. The rows of posts are arranged one in front of the other and the posts in each row are numbered consecutively (see Fig. 5) and corresponding consecutive numerals 32 are arranged on the front of the shelf 20. When the shelf 20 is pulled out, as shown in Fig. 5, then any one of the cylinder records 21 can be removed from the corresponding post 30 or 100 31. The outward sliding movement of the tray 20 is limited by stop pins 33 depending from the partition 13 and adapted to be engaged by the back of the tray when the latter is pulled out to its full extent. The 105 110

- cells or pigeonholes 22 are arranged in horizontal and vertical rows, and the vertical rows are numbered consecutively as indicated at 34 in Fig. 1.
- 5 In order to readily file the music or to readily find any piece of music for removal as desired, use is made of an index book 40 illustrated in Fig. 3. The leaves of the index book 40 are provided with index tabs 41 bearing identification characters, preferably the letters of the alphabet. The front face of each leaf is preferably provided with a title column 42, a portion of which is used for receiving the title of sheet music and another portion is used for receiving the titles of phonographic disk records. The rear face of each sheet is provided with two title columns 43 and 44, of which the column 43 is adapted to receive the titles of roll music and the column 44 is adapted to receive the titles of phonographic cylinder records. It is understood that the titles in the columns have their first letter correspond to the index letter 41 of the corresponding leaf. Adjacent the title column 42 is arranged a number column 45 containing opposite to each title four numerals of which the first numeral indicates the corresponding section 10 or 11, the second numeral indicates the corresponding compartment in that section, the third numeral indicates the number of the book in that compartment, and the fourth numeral indicates the corresponding index numeral 29 of that particular book. Thus any piece of sheet music or phonographic disk record entered in the column 42 and having received its identification numerals is placed in the leaf of a corresponding book in the corresponding compartment of a corresponding section, and when it is desired to remove a piece of sheet music or a disk record of which the title is known, it is only necessary to refer to the index book on the corresponding page to find the title and the numbers 45 associated therewith to permit the user to readily locate the music or the disk record in the cabinet and to remove it therefrom if desired.
- 50 To one side of the column 43 on the back of the page is arranged a number column 46 which contains a set of numerals opposite each title, and the first numeral of the set of numerals indicates the cabinet section, the second indicates the corresponding compartment in that section, and the third number indicates the corresponding cell or pigeonhole marked correspondingly at the top. The title column 44 has arranged to one side a numeral column 47 adapted to receive a set of numerals opposite each title, and the first of each set of numerals refers

to the cabinet section, the second to the corresponding compartment in that section, and the third to the corresponding numeral in 65 the tray 20.

It is understood that the sheet music, the roll music and the phonographic disk records are provided with a set of numerals corresponding to that given opposite to its 70 title in the index book 40, as will be readily understood by reference to Figs. 3, 4, 6 and 7.

From the foregoing it will be seen that the user of the cabinet can readily file any 75 one piece of music in the cabinet after having entered the title in the index book and given the piece of music its set of identification numerals likewise entered in the index book alongside the title. By reference 80 to the index book the user can quickly find the set of identification characters of any piece of music filed in the cabinet and of which the title is known, and then by the use of the identification characters can locate the piece of music in the cabinet and remove it therefrom without disturbing any other piece of music filed in the cabinet. Although I have shown and described the cabinet as provided with two sections each 90 divided in two compartments I do not limit myself to this particular construction as one section, say section 10, may be used for the several types of music referred to. On the other hand, the sections and compartments may be increased in number to meet the requirements of the user. It will also be noticed that a very large number of pieces of music can be filed in a cabinet of comparatively small dimensions. 100

Having thus described my invention, I claim as new and desire to secure by Letters Patent:—

A music filing cabinet, comprising a casing divided into three compartments one 105 above the other, the upper compartment being for filing sheet music and phonographic disk records in upright position, the compartment being provided with consecutively numbered and vertically disposed 110 books each having its leaves numbered consecutively, the lower compartment being for filing roll music and having cells each adapted to receive a roll singly and arranged in vertical and horizontal rows, the 115 vertical rows being numbered consecutively, and a tray slideable transversely in the intermediate compartment and provided with rows of posts each adapted to receive a phonographic cylinder record singly, the 120 post rows being arranged one in front of the other and the posts in each row being numbered consecutively.

PATRICK T. LARKIN.
